RAILWAY TRAFFIC CONTROLLING
APPARATUS

Lloyd V. Lewis, Pittsburgh, Pa., assignor to The
Union Switch & Signal Company, Swissvale,
Pa., a corporation of Pennsylvania

Application January 12, 1946, Serial No. 640,753

8 Claims. (Cl. 246—3)

1

My invention relates to railway traffic controlling apparatus and more particularly to an improved system of circuits for use in centralized traffic control machines for the remote control of traffic movements in either direction on single track railroads.

The apparatus of my invention is an improvement upon that shown in Fig. 1 of an application for Letters Patent of the United States, Serial No. 501,254, filed September 4, 1943, by Henry S. Young, for Railway traffic controlling apparatus, now Patent No. 2,420,579, issued May 13, 1947.

In the centralized traffic control system shown and described in this Young application, an absolute permissive block system controlled by continuous track circuits is provided for governing traffic movements in two directions over a stretch of single track railroad having passing sidings at spaced locations. The movement of traffic into the blocks is governed by head block signals, located at the opposite ends, and the blocks are divided into block sections, with intermediate signals for two directions located at the junctions of the sections. All of the signals for a block are controlled over a system of reversible line circuits in accordance with traffic conditions as manifested by the track relays of the adjacent block sections. The head block signals are made subject to manual control from a central point, such as a train dispatcher's office, by the provision of a code type communication system, having field stations located at the block ends for receiving control codes transmitted from the office, by which control relays for the signals are operated in accordance with the positions of signal levers at the office, and by which traffic relays are operated to govern the direction of energization of the reversible line circuit system, in accordance with the position of a master directional relay at the office. The station apparatus of the code system also serves to transmit indication codes to the office for indicating wayside conditions to the operator by the lighting of various lamps associated with a track diagram, and for imposing restrictions upon the issue of control codes by the operator. A feature of the indication system is the provision of a block indicator for each block for indicating the presence of a train at any point therein, controlled jointly by codes transmitted from both ends of the block which reflect the condition of different portions of the reversible line circuit system by which the signals are controlled.

2

The centralized traffic control system also includes provisions for releasing electric locks for outlying hand throw switches, by cooperation between the central office operator and the crew of a train, involving means for enabling the operator to set up the reversible line circuit system so as to permit a switch to be unlocked to enter the block from a side track only when the entire block is vacant, and to then proceed through the block in a selected direction under the protection of the signal system.

The principal object of my invention is to provide an improved system of traffic direction control for use in centralized traffic control of the type referred to, or for use in other systems having generally similar requirements, such as those employing cascade-connected reversible track circuits in place of line circuits, as shown, for example, in Letters Patent of the United States No. 2,344,333, issued March 14, 1944, to James J. Van Horn, for Railway traffic controlling apparatus, which patent was re-issued as No. 22,780, on Aug. 13, 1946.

The traffic direction controlling apparatus of my invention functions in such a manner that the control of the traffic relays at the ends of the blocks requires no special action by the operator, but is effected as a result of the usual operations of reversing the signal lever for the head block signal which is to be cleared, followed by the operation of the associated code starting button whereby the transmission of a code for clearing the signal is initiated.

In the event the traffic direction set up is the opposite to that desired, but the block is unoccupied and all of the head block signals are at stop, as would be the case, for example, if the operator desired to authorize an eastbound train to enter a block which has just been vacated by a westbound train, the operations mentioned result first in the movement of the master directional relay at the office to a position marking the desired traffic direction, and then in the transmission of control codes to both ends of the block whereby the traffic relays are operated to corresponding positions so as to reverse the direction of energization of the line circuit system, causing the intermediate signals for one direction to be put to stop, and then the signals for the other direction are cleared automatically as the line circuit system becomes energized section by section. The code transmitted to the entering end of the block also operates a signal control relay thereby causing the head block signal at that end to

clear in response to the energization of the line circuit system.

The wayside apparatus for outlying switch control includes an indication relay at the switch having contacts controlling the reversible line circuit system which when closed indicate that the switch is locked in its normal position. To reverse the switch to permit a train to enter the main track, the crew of the train after securing permission from the central office operator and removing a padlock or the like, open a local circuit to release the switch indication relay, which relay upon releasing divides the line circuit system into two portions and connects a line relay at the switch location to each portion. When the operator grants permission to unlock the switch he also operates a switch lock lever to the right or left in accordance with the direction of movement of the train, thereby operating the master directional relay in a corresponding direction, provided the block is unoccupied and the head block signals at both ends are at stop, and initiating the transmission of codes to both ends of the block by which the traffic relays are operated to supply current to the line circuit system at both ends. The resulting energization of the line relays referred to, in the event the entire block is unoccupied, allows the train crew to unlock the hand throw track switch and to reverse it to permit their train to enter the block.

The master directional relay at the office is of the polar stick type or the like, arranged to be held in its last operated position when deenergized, and is governed by the code-controlled indication relays so that it is held deenergized following the reception of a code indicating that a head block signal is at clear, or of one indicating the presence of a train in the block.

One feature of my invention is the provision of means for maintaining the directional relay normally deenergized, its circuits being closed momentarily in response to the operation of a starting button or switch lock lever under the proper conditions as reflected by the code indication system.

Another feature of my invention is the provision of means for rendering each starting button effective to initiate the transmission of codes to both ends of the block but once, for each operation of the master directional relay.

Other features include means for preventing the operation of the master directional relay by lever operation except when codes are initiated for establishing the corresponding traffic direction, and for enabling the operator to regain control of the master directional relay after it has been locked deenergized, in order to enable him to restore the original direction of traffic if for any reason the reversal of traffic direction is not required or cannot be effected due to a fault in the wayside circuits.

Other objects, purposes and features of my invention will be pointed out as the description proceeds.

I shall describe one form of apparatus embodying my invention and shall then point out the novel features thereof in claims.

Referring to the accompanying drawings, Fig. 1 shows the circuits embodying my invention contained in one section of the office control machine of the centralized traffic control system, including the control panels for two stations located at the opposite ends of a single track block arranged as indicated by the miniature track diagram at the top of the view, while Figs. 2A and 2B, taken

together, show a plan of the corresponding stretch of railway track together with the wayside apparatus and circuits controlled by the apparatus of Fig. 1. The wayside circuits as shown herein correspond generally to those of Figs. 2A, 2B and 2C of the Young patent hereinbefore referred to, arranged in a condensed form and omitting the circuits for the control of the power operated track switches 1W and 3W at the ends of the block and also those for the control of the leaving signals 2L and 2R, as well as those for other features, a description of which is not needed for an understanding of my invention.

To simplify the drawings, in lieu of showing the various sources of current for energizing the relays, I have shown only their terminals, the positive or supply terminal being identified by the reference character B, and the negative or common return terminal by the reference character C, in each instance.

Similar reference characters refer to similar parts in each of the views.

The code control system

The code system employed for communication between the office and the wayside stations corresponds generally to that shown in Letters Patent of the United States No. 2,229,249, issued to me on January 21, 1941, and specifically to a modification thereof shown in an application for Letters Patent of the United States, Serial No. 496,907, filed July 31, 1943, by Arthur P. Jackel, now Patent No. 2,411,375, issued Nov. 16, 1946, which system is described in a publication entitled "Manual 506-A, of the Union Switch and Signal Co. of Swissvale, Pennsylvania."

Consideration of the detailed mode of operation of the code system is not needed for an understanding of my invention, and it is deemed sufficient to point out that the code system provides seven channels for the transmission of controls from the office to a selected station, and seven other channels for the transmission of indications from any station to the office, only one station at a time, over a single line circuit, without interference. For simplicity, the various channels are designated by numbers and are represented herein by direct wire connections. Each control code transmitted from the office is initiated by the manual energization of a starting relay, such as the relay O1ST or O3ST, Fig. 1, of which one is provided for each office panel. Each starting relay is picked up by the momentary closing of a contact *a* or *b* of a starting button 1STB or 3STB or of the switch lock lever 2WL. Lever 2WL is of the "push-turn" type, its contacts *a* and *b* closing whenever its rotary contacts *c* and *d* are moved from one operative position to another. Each starting relay initiates a code by closing its contact *c*, and is held energized over a stick circuit until its code call is transmitted, in the manner described in Patent No. 2,229,249.

Each control code includes a distinctive code call by which a selector relay O1S or O3S for the same panel, together with a delivery relay 1D or 3D, Fig. 2A or 2B, at the corresponding field station No. 1 or No. 2, are energized, only one panel and station at a time, thereby establishing the control channels for communication between the selected panel and station. At the office each channel is supplied with current or not, depending upon the control to be effected, and at the selected station, a group of polar stick relays such as the relays 2RFS, 2WLS, etc., are operated to normal or reverse in accordance with the condition of a

Series of register relays 1F2, 1F4, etc., which are interposed in the channels. Of the seven control channels which the system provides, only channels 2, 4, 5 and 7 are shown herein.

The master directional relay by which the direction of traffic movements is governed is relay LP, Fig. 1. At station No. 1, a traffic relay 2RFS, and at station No. 2, a traffic relay 4LFS, is operated over channel 2 by different codes to a position corresponding to that of relay LP. At station No. 1, a switch control relay 2WLS for the hand throw switch 2W is controlled over channel 4, by a repeating relay 2WLP for the switch lock lever 2WL of Fig. 1, relay 2WLP also controlling the traffic relay 4LFS over channel 2, in response to a code initiated by the operation of lever 2WL. At station No. 1, the signal control relay 2RHS for signals 2RA and 2RB is operable to reverse over channel 7, when the signal lever 2SG is in its right-hand reverse position, and at station No. 2, the signal control relay 4LHS for signals 4LA and 4LB is operable to reverse over channel 5 when the signal lever 4SG is in its left-hand reverse position.

The signaling system

Considering now the wayside circuits of Figs. 2A and 2B, the head block signals as shown are of the searchlight type, each having an operating mechanism identified by the reference character G prefixed by the signal designation, such as the mechanism 4LAG for signal 4LA. Each signal mechanism when energized in a normal or reverse direction conditions its signal to indicate proceed or caution and when deenergized, to indicate stop. The intermediate signals 21, 22, 23 and 24, which in the Young patent are of the searchlight type, are shown herein as of the color light type, having green, yellow and red lamps for indicating proceed, caution or stop. The lamp circuits for the intermediate signals as well as the mechanisms G for the head block signals are governed by polarized relays, each identified by the reference character HD prefixed by the designation of the corresponding signal. The signal relays HD are all controlled over the reversible line circuit system, which as shown, is divided into three circuit sections corresponding to the three block sections, the circuit for each section including front contacts of the track relays TR for the adjacent track sections. Each signal relay HD is arranged to be energized in series with an approach relay AR. Each relay AR at an intermediate signal location governs the lighting of the correspondingly numbered signal in a well-known manner, while those at the head block locations govern the transmission of indications by the remote control system for indicating the occupancy of portions of the single track block.

Each intermediate signal relay such as relay 21HD when energized supplies current of normal polarity to the line circuit for the signal relay such as relay 23HD for the next signal in the rear, and has associated therewith the usual directional stick relay such as relay 21S, which becomes energized when a train passes the corresponding signal at proceed or caution and closes its front contacts to supply current of reverse polarity to the line circuit for the next section in the rear, and is held energized only until the associated signal relay HD is again energized. At the ends of the block, the polarity of the current supplied to the line circuit system is controlled by a pole changer relay such as relay 2LAPC or 4RAPC controlled by the mechanism for the leaving signal 2LA or 4RA over a circuit shown in the

Young patent which is closed only when the signal indicates proceed, but which in other respects is similar to the circuit for the relay 2RAPC or 4LAPC shown herein. The line circuit system is energized over a front contact of an approach locking relay 2RAS or 4LAS which is controlled in a conventional manner, as shown in the Young patent, by the stop indication relay 2RGP or 4LGP for the adjacent entering signals and by suitable time locking apparatus, not shown herein, for preventing the clearing of the opposing signals except when traffic conditions are proper.

As shown, the contacts *a* and *b* of the traffic relays 2RFS and 4LFS occupy their left-hand positions and the sections of the reversible line circuit system are thereby energized in cascade at their left-hand ends as required for traffic movements from right to left. More particularly, the left-hand contacts *a* and *b* of relay 2RFS connect terminals B and C of the local source of current at station No. 1 over contacts *a* and *b* of relay 2LAPC to the left-hand section of the line circuit system, whereby current is supplied over the front contacts of relay 2RAS and of the track relays 1TR, 2TR and 21TR for the adjacent track circuits of the first section of the block, and back contacts of relays 22S and 22HD, to energize the signal relay 21HD in series with the approach relay 2LAR. Relay 21HD is energized in the reverse direction, as shown, to condition signal 21 to indicate caution, when signal 2LA indicates stop or caution, while relay 21HD is energized in the normal direction to condition signal 21 to indicate proceed, when signal 2LA indicates proceed, in which case relay 2LAPC assumes its energized position. The closing of the front contacts *a* and *b* of relay 21HD connects terminals B and C of the local source of current at the location of signals 21 and 22 to the intermediate section of the line circuit system, over back contacts of relay 21S, the connection to terminal B including a back contact of relay 22HD, the winding of relay 21AR and a front contact of relay 21TR. When relay 21HD is picked up, current of normal polarity is supplied over front contacts of the track relays 22TR and 23TR of the track circuits for the intermediate section of the block and over front contacts *a*, *b*, *c* and *d* of relay 2NWP, and back contacts of relays 24S and 24HD, to energize the signal relay 23HD in the normal direction, in series with the approach relay 21AR and thereby condition signal 23 to indicate proceed. The closing of front contacts *a* and *b* of relay 23HD completes a similar circuit from terminals B and C of the source at the location of signals 23 and 24, whereby current of normal polarity is supplied over front contacts of the track relays 24TR, 4TR and 3TR for the third section of the block, and the left-hand contacts *a* and *b* of the traffic relay 4LFS, to energize the signal relay 4LHD in the normal direction in series with the approach relay 23AR. If now the signal control relay 4LHS is operated to reverse, the closing of its contact *a* completes a circuit over front contact *b* of relay 4LHD whereby mechanism 4LAG is energized, over a contact N if switch 3W is normal, or mechanism 4LBG is energized, over a contact R if switch 3W is reversed, each in the normal or reverse direction in accordance with the position of the polar contacts *e* and *f* of relay 4LHD, as will be readily apparent from the drawing.

When the traffic relays 2RFS and 4LFS are operated to close their right-hand contacts *a*

and *b*, the signal relays **21HD**, **23HD** and **4LHD** and the approach relays **2LAR**, **21AR** and **23AR** all release, holding signals **21**, **23**, **4LA** and **2LB** at stop. Then relays **24HD**, **22HD** and **2RHD** become energized in cascade, each in series with one of the approach relays **2RAR**, **24AR** and **22AR**, the circuits for the two directions being similar. Signals **24** and **22** will then be conditioned to indicate caution and proceed, respectively, and signal **2RA** or **2RB**, depending upon the position of switch **1W**, may be cleared by reversing relay **2RHS**.

It will be understood that as a train governed by signal **4LA**, for example, proceeds through the block, a directional stick relay **23S** becomes energized in response to the release of the track relay **23TR**, during the release period of relay **23HD**, over circuits similar to those shown for relay **21S**, and when the block section in the rear of signal **23** is vacated, front contacts *a* and *b* of relay **23S** connect terminals **B** and **C** to the line circuit system to energize relay **4LHD** in the reverse direction whereby signal **4LA** or **4LB** may be conditioned to indicate caution. Similarly relay **21S** is energized upon the release of relay **21TR**, during the release period of relay **21HD**, whereby relay **23** may be conditioned to indicate caution to govern a following train, or if relay **2NWP** is released, to permit relay **2WAR** to be energized as required to permit a following train to enter the block over switch **2W** reversed, as hereinafter described.

Outlying track switch control

The hand throw switch **2W** is normally locked in its normal position as required for main track movements by the magnet **2WLM** of an electric lock having a locking segment **25** mounted on a shaft carrying the contacts **47** and **49**, the movement of which is limited by a locking dog on the magnet armature. Signals **22** and **23** which govern train movements over switch **2W** are prevented from clearing except when the switch is locked normal by including contacts of the switch indication relay **2NWP** in the line circuit as already described. Relay **2NWP** is normally energized over a circuit which includes a contact **N** controlled by switch **2W** which is closed only when the switch is locked normal, and also includes contact **49** which is closed only when the hand throw lever **3** is locked normal by the lock magnet **2WLM**. Segment **25**, and contacts **47** and **49** are also held normally in the position shown by the bail **50** of a padlock, which may be removed by the crew of a train after obtaining authority from the operator to unlock the switch. Segment **25** may then be moved a short distance to open the circuit including contact **49**, releasing relay **2NWP**, and to close contacts **46**—**47** in the circuit for magnet **2WLM**.

For a train movement from the main track to the side track, magnet **2WLM** will then become energized, provided the train has occupied the track section in approach to the switch, for a time sufficient to complete the operation of a time element relay **TE** controlled over a back contact of the track relay **22TR**.

For a train movement out of the side track, the central office operator will have cooperated by moving his switch lever **2WL** to the left or right, according to the direction the train is to proceed after it enters the block, thereby initiating two control codes, one of which operates relay **2WLS** to reverse and also operates relay **2RFS** to the left or right to correspond with the posi-

tion of lever **2WL**, the other operating relay **4LFS** to the right, so that terminals **B** and **C** become connected to the line circuit system at both ends, in lieu of at one end only, corresponding to the exit end for the established traffic direction. If the block is unoccupied, current is supplied over the line circuit system from both ends to energize the line relays **2WAR** and **2EAR** at the switch location, provided contact **49** has been opened to release relay **2NWP**, and magnet **2WLM** may then be energized over contacts **46**—**47**. This permits segment **25** to be moved to its full reverse position, in which lever **3** is unlocked to permit switch **2W** to be operated to reverse.

In the foregoing, it has been assumed that the block is unoccupied, in which case the master directional relay **LP** is free to respond to the switch lever operation and either direction of traffic movement may be established. Switch **2W** may also be unlocked while the block is occupied, provided the train therein has passed the switch location. In this case relay **LP** is held deenergized, retaining the established traffic direction, but one or the other of the two codes transmitted in response to the reversal of lever **2WL** will be effective to energize the line circuit system in the rear of the train occupying the block, and when this train passes switch **2W**, the release of relay **2NWP** will permit the energization of the corresponding one of the line relays **2WAR** or **2EAR**. The other of these relays will then become energized when the main line train vacates the block section containing switch **2W**, by current supplied to its line circuit over front contacts of the directional stick relay **21S** or **24S**.

The code indication system

Each indication code is initiated by the release of a normally energized starting relay such as relay **1ST** at station No. 1, which as shown by the circuits occurs either in response to a change in the position of one or more of the indicating relays or due to the operation of the delivery relay **4D**, when a control code is received. In each code initiated by relay **1ST**, a selector relay **1S** at the station is energized along with a delivery relay **O'D** in the corresponding office panel, in response to the station code call, to extend the indication channels **9**—**15** from the selected station to the corresponding office panel. At station No. 1, only channels **10**, **14** and **15** are shown herein, over which the indication stick relays **1TK**, **2RBK** and **2RHK** are energized in response to the closing of back contacts of the corresponding indicating relays **1TKS**, **2RBP** and **2RGP** at station No. 1. The release of the similar starting relay **3ST**, at station No. 2, initiates a code in which a selector relay **3S** and a delivery relay **O'D** are energized to control the indication stick relays **3TK**, **4LBK** and **4LHK** over channels **10**, **12** and **14**, and back contacts of relays **3TKS**, **4LBP** and **4LGP**, respectively.

Relays **1TK** and **3TK** are the usual track indication relays which control the lamps **1TKE** and **3TKE** in the "OS" sections of the track diagram, and which also usually control pen magnets in a train graph as described in Patent No. 2,229,249. To prevent the loss of the indication of the arrival of a train at a station in the event the transmission of indications is delayed and the train vacates the controlling track section before an indication of its occupancy is transmitted, a storage relay such as relay **1TKS** is provided.

When a train enters the track section including switch **1W** and releases the track relay **1TR**, the opening of contact *a* of relay **1TR** releases relay

1TKS, which relay by momentarily opening its contact *c* releases the starting relay **1ST** to store the indication code for transmission as soon as the code line becomes available. Relay **MSP** is energized during the transmission of this code as described in Patent No. 2,229,249, and relay **1ST** is reenergized during the transmission of this code. The contacts of relays **MSP** and **1ST** in the circuit for relay **1TKS** serve to hold this circuit open until the code is fully transmitted, thereby insuring the energization of the track indication relay **1TK** over channel **10**, even though its transmission occurs after the switch section is vacated and relay **1TR** is reenergized.

Relays **2RBK** and **4LBK** are block indication relays which differ from the similarly designated relays of the hereinbefore referred to Young patent in that they are normally deenergized. Contacts *c* of these relays jointly control a block indication lamp **BKE** in the track diagram, which lamp is lighted to indicate the presence of a train in any section of the single track block.

When the right-to-left direction is set up, relay **4LBP**, the release of which initiates the transmission of an indication code for energizing relay **4LBK**, is held energized, as shown, over the neutral contact *a* and the normal polar contact *d* of the signal relay **4LHD**, only when the intermediate and right-hand block sections are both unoccupied, while relay **2RBP**, the release of which initiates the transmission of an indication code for energizing relay **2RBK**, is held energized, as shown, over the left-hand contact *c* of relay **2WLS** and front contact *a* of the approach relay **2LAR**, only when the left-hand block section is unoccupied.

When the left-to-right direction is established, relay **2RBP** is energized over contact *c* of relay **2WLS** and contacts *a* and *d* of relay **2RHD** provided the left-hand and intermediate block sections are unoccupied, and relay **4LBP** is energized over contact *a* of relay **4RAR**, provided the right-hand block section is unoccupied.

A modification of this arrangement is required when the block contains more or less than three sections, a description of which herein is deemed unnecessary.

Lamp **BKE** is also lighted whenever the switch control relay **2WLS** is operated to its reverse position, because contact *c* of relay **2WLS** in the circuits for relay **2RBP** is then open and relay **2RBP** remains released to hold relay **2RBK** energized regardless of block conditions.

The signal indication relays **2RHK** and **2LHK** control lamps associated with the signal levers as in the Young patent hereinbefore referred to but to simplify the drawings these are not shown herein.

The traffic direction control system

Referring to Fig. 1, the circuits for the master directional relay **LP** differ from those of the corresponding relay of the above-mentioned Young application and are arranged in a novel manner to include therein contacts *d* of the starting buttons **1STB** and **3STB** as well as contacts of a normally deenergized direction locking relay **LPS**. When traffic conditions as reflected by the indication relays are such as to allow the position of relay **LP** to be changed, back contacts *b* of the signal, track and block indication relays being closed, the operation of the signal lever **2SG** to its right-hand reverse position, or of lever **4SG** to its left-hand reverse position, completes a circuit at the lever contact *b* over contact *b* of relay **LP**

for energizing relay **LPS**, provided a change in the direction of traffic designated by relay **LP** is necessary in order to clear the signal controlled by the operated signal lever. When relay **LPS** picks up it becomes disconnected from its pick-up circuit by the operation of its contact *a*, and is held energized over a stick circuit having multiple connections to terminal **B** of the local source at back contacts *c* of the starting relays **O1ST** and **O3ST**, so that relay **LPS** is held energized until control codes have been initiated, or stored for transmission, to the stations at both ends of the block.

If a signal lever is operated to reverse in preparation for the transmission of a control code which does not involve a change in the established traffic direction, relay **LPS** remains released and the pressing of the starting button **1STB** or **3STB** then completes a circuit at its contact *a* only, whereby the associated starting relay **O1ST** or **O3ST** is energized, but when relay **LPS** is energized by the operation of a signal lever as described, the pressing of the starting button associated with that signal lever completes three other circuits, in addition. The closing of contact *c* of the operated button completes a circuit over contact *f* of relay **LPS** to energize a block repeating stick relay **BKS**, and the closing of contact *d* of the operated button completes a circuit over contact *b* or *c* of relay **LPS** for operating relay **LP** to the position designating the traffic direction to be established, while the closing of contact *b* of the operated button completes a circuit over the reverse contact *c* of the operated signal lever and contact *g* or *h* of relay **LPS** for energizing the starting relay of the adjoining panel for the station at the opposite end of the block. It follows that two codes are initiated, for operating the traffic relays **2RFS** and **4LFS**, respectively, in accordance with the open or closed condition of channel 2 as determined by contact *c* of relay **LP** so that these relays both assume positions corresponding to that of relay **LP**.

It will be seen that relay **LP** is free to be operated only when the block is unoccupied, as indicated when both of the block indication relays **2RBK** and **4LBK** have been released by codes reflecting the energized condition of the reversible line circuit system. The interruption of the wayside circuits prevents the transmission of indications of the unoccupied block condition while the traffic direction is being changed, but during this period, it is desirable to permit relay **LP** to remain operable to either position so that the original traffic direction can be restored if the operator so desires, or if the reversal cannot be effected, due to a fault. This is accomplished by the provision of the block repeating relay **BKS**, which is energized along with relay **LP** as above described, and "stores" the block clear indication, in effect, to maintain relays **LP** and **LPS** operable, by closing its front contact *b* in the circuits for these relays, until the wayside circuits are re-established. When relay **BKS** picks up, it closes circuits momentarily over its contacts *a* and *e* to pick up the block indication relays **2RBK** and **4LBK** locally, placing them in condition to be released by codes indicating the unoccupied block condition, and the closing of the front contacts *b* of the block indication relays completes a stick circuit for relay **BKS**, which relay therefore is held energized until both block indication relays release to indicate the reenergization of the line circuit system. During the period of traffic re-

versal; the circuits for the direction indication lamp EFE or WFE and for the block indication lamp BKE are held open at back contact *c* of relay BKS.

It will be seen that relay LPS replaces the two relays EFK and WFK of the Young application, and of the Van Horn patent hereinbefore referred to, with respect to the control of code transmission, but with an improved mode of operation, while relay BKS replaces relays EFK and WFK with respect to the control of the block indication relays. The circuits for the relays LPS and BKS as disclosed herein are an improvement upon those for similarly designated relays shown in an application for Letters Patent of the United States, Serial No. 567,188, filed December 8, 1944, by Frank T. Pascoe and Arthur L. Jerome, for Railway traffic controlling apparatus, which issued as Patent No. 2,411,387, on November 19, 1946.

The operation of the switch lock lever 2WL is also effective to initiate the transmission of codes to both ends of the block, its contacts *a* and *b* closing momentarily to energize the starting relays O1ST and O3ST whenever lever 2WL is rotated from one operating position to another. Contact *c* of lever 2WL controls relay LP in accordance with the desired direction of traffic movement, and contact *d* of lever 2WL controls a repeating relay 2WLP by which the circuits governed by relay 2WLP are interlocked by those controlled by the signal levers, that is, the circuit for 2WLP includes back contact *b* of relay BKS and back contacts *d* of relays 2RHK and 4LHK, and the circuits for relays LPS and BKS include back contacts *e* and *a* of relay 2WLP.

Operation.

I shall first assume that the system is set up for the right-to-left direction and is in its normal condition as shown, with lamp WFE lighted but with signals 4LA and 4LB at stop, and shall trace the operations for clearing signal 2RA.

The operator moves lever 2SG to the right, which completes a circuit from terminal B at back contact *b* of relay 2RBK over back contacts *b* of relays 4LBK, 1TK, 3TK, 2RHK and 4LHK, the right-hand contact *b* of signal lever 2SG, the normal or right-hand contact *a* of lever 4SG, left-hand contact *b* of relay LP, back contact *a* and winding of relay LPS to terminal C at back contact *e* of relay 2WLP. Relay LPS picks up and completes a stick circuit at its own front contact *a* extending to terminal B at back contacts *c* of relays O1ST and O3ST.

The operator then presses button 1STB, energizing relay O1ST over the button contact *a*, and energizing relay O3ST over the circuit including the button contact *b*, the right-hand contact *c* of lever 2SG and contact *g* of relay LPS, also energizing relay BKS over the circuit extending from terminal B at contact *a* of relay 2WLP, contact *f* of relay LPS and contact *c* of button 1STB, and energizing the upper winding of relay LP over the circuit including contacts *b* of the indication relays and of lever 2SG, contact *a* of lever 4SG, contact *d* of button 1STB, and contact *b* of relay LPS, whereby relay LP is operated to close its right-hand contacts.

The starting relays O1ST and O3ST when both are operated open the stick circuit for relay LPS, which relay therefore releases after a brief period, during which circuits are completed momentarily over contacts *d* and *e* of relays BKS and LPS to pick up relays 2RBK and 4LBK,

which relays thus assume positions corresponding to the occupied block condition and are held energized over their stick circuits including their own front contacts *a* and the back contacts of the delivery relays O1D and O3D, respectively, and by closing their front contacts *b*, complete a stick circuit including back contacts *d* of relays 1TK and 3TK and front contact *a* of relay BKS for holding relay BKS energized. The opening of back contact *c* of relay BKS extinguishes lamp WFE and maintains lamps EFE and BKE dark, while the closing of front contact *b* of relay BKS prepares a circuit for restoring relay LP which includes its lower winding and the open contacts *b* of lever 4SG and *d* of button 3STB and is also open at contact *c* of relay LPS; the circuit for which as traced above is now open at contact *b* of relay LP.

The closing of front contacts *c* of relays O1ST and O3ST initiates the transmission of control codes to the corresponding stations Nos. 1 and 2 at the opposite ends of the block, as described in Patent No. 2,229,249. In the code initiated by relay O1ST, relays O1S and 1D are operated, and since the connection from contact *c* of relay LP to channel 2 over contact *e* of relay O1S is open, relay 1F2, Fig. 2A, is not operated and relay 2RFS is operated to close its right-hand contacts *a* and *b*, by relay 1D. Channel 4 is open, so that relay 2WLS is operated to the left, but channel 7 is energized over contact *g* of relay O1S, contact *d* of lever 2SG and contact *c* of relay LP, so that relay 2RHS is operated to the right. In the code initiated by relay O3ST, relays O3S and 3D are operated, energizing channel 2 only, over contacts *c* of relay LP and contact *e* of relay O3S, to operate relay 4LFS to the right.

Relays 2RFS and 4LFS in their right-hand positions reverse the direction of energization of the line circuit system as hereinbefore described. Relay 4LBP is picked up by relay 4RAR, and relay 2RBP by relay 2RHD, and since contact *a* of relay 2RHS is closed, relay 2RHD energizes mechanism 2RAG to clear signal 2RA, and to release relay 2RGP.

These operations result in the initiation of one or more indication codes from each station, whereby relays 2RBK and 4LBK are released, thereby releasing relay BKS and lighting lamp EFE to indicate the traffic direction established, and relay 2RHK becomes energized to indicate the clearing of the signal and opens its back contact *b* to lock relay LP reversed.

Usually these codes will all be transmitted before the train governed by signal 2RA enters the block; but if the code system controls a large number of stations and the traffic is heavy, it may happen that the train will pass signal 2RA at clear and enter the block before the system has an opportunity to transmit the indication code by which relay 2RHK is energized and relay 2RBK released. In this case, the first code received from station No. 1, following the transmission of the control codes for reversing the traffic direction, will be the "OS" code, energizing relay 1TK, even though the train has vacated the "OS" section before this code is transmitted, due to its storage by relay 1TKS. The opening of contact *b* of relay 1TK locks relay LP, and the opening of contact *d* of relay 1TK releases relay BKS, thereby rendering relay 2RBK effective, provided it is maintained energized by this code, to light lamp BKE to indicate the occupied block condition, and to hold relays LP and LPS de-energized. Lamp EFE also becomes lighted to

13

indicate the established direction of traffic as in the preceding example.

It will be seen that lamp BKE indicates whether or not the block is occupied only when lamp EFE or WFE is lighted to indicate that the corresponding direction of traffic is established, and that while the traffic direction is being established all three lamps are dark.

It may be that the operator after having initiated the reversal of traffic as above described will wish to restore the original traffic direction, due to a change in orders or in case it is found that the reverse direction cannot be set up due to a fault. He will first assure himself that the entering signal is at stop with its control relay 2RHS normal, by transmitting a code for operating relay 2RHS to normal. The operation of the delivery relay 1D by this code releases relay 1ST thereby initiating the transmission of an indication code, in which, if signals 2RA and 2RB are at stop, channel 15 is deenergized, so that relay 2RBK remains released.

If a train has already entered the block at this time, under the control of signal 2RA or 2RB, this indication code will cause relay 1TK to become energized over channel 10, releasing relay BKS to light lamps EFE and BKE, and relay 2RBK or 4LBK will remain energized to hold relay LP reversed and relay LPS released until the train vacates the block.

If relay 1TK is not energized by this indication code, the operator may restore the original direction of traffic by moving the signal lever 2SG to its normal center position and then moving lever 4SG to the left, thereby energizing relay LPS over the circuit extending from terminal B at front contact b of relay BKS, over back contacts b of relays 1TK, 3TK, 2RBK and 4LHK, left-hand contact b of lever 4SG, contact a of lever 2SG, right-hand contact b of relay LP, back contact a and winding of relay LPS to terminal C at contact e of relay 2WLP. The operator will then press button 3STB, energizing relays O1ST and O1ST and the lower winding of relay LP, thereby operating relay LP to the left, initiating the transmission of a code to station No. 1 in which channel 2 is energized, and one to station No. 2 in which channel 5 is energized. The effect of these codes is to clear the signal 4LA or 4LB, as will be readily understood, resulting in the transmission of indication codes for releasing relays 2RBK and 4LBK, thereby releasing relay BKS and lighting lamp WFE, and energizing relay 2LHK to indicate the clearing of signal 4LA, thereby locking relay LP in the position shown.

I shall now trace the operations involved in unlocking switch 2W, assuming that the right-to-left traffic direction is set up as shown, and that the crew of a train on the siding at switch 2W has communicated with the operator by telephone, requesting authority to enter the block and to move their train in the opposite direction, that is, toward the right.

The operator moves lever 2WL to its right-hand position, leaving the signal levers 2SG and 4SG both in their normal positions, as shown. Contacts a and b of lever 2WL close momentarily, energizing the starting relays O1ST and O3ST to initiate the transmission of control codes to stations at both ends of the block. The closing of contact d of lever 2WL energizes relay 2WLP over the circuit extending over back contacts d of relays 2RBK and 4LHK to terminal B, at back contact b of relay BKS, and the closing of the right-hand contact c of lever 2WL energizes the

14

upper winding of relay LP, over front contact b of relay 2WLP and back contacts b of the indication relays, so that relay LP is operated to its right-hand position to correspond with the position of lever 2WL.

In the code transmitted to station No. 1, channel 2 is not energized, but channel 4 is energized over contact d of relay 2WLP, and in the code transmitted to station No. 2, channel 2 is energized over contact c of relay 2WLP and also over the right-hand contact c of relay LP. Consequently these codes serve to operate each of the relays 2WLS, 2RFS and 4LFS to the right, in which case, as will be clear from Figs. 2A and 2B, the line circuit system is supplied with current at both ends, energizing relays 21HD and 24HD and thereby conditioning signals 21 and 24 to indicate caution, and if segment 25 is operated by the train crew to open contact 49 and thereby release relay 2NWP, the line relays 2WAR and 2EAR will both become energized to complete a circuit for the lock magnet 2WLM to permit switch 2W to be unlocked. The approach relays 2LAR and 4RAR are both energized, likewise the indicating relay 4LBP, but relay 2RBP remains released due to the opening of contact c of relay 2WLS. The block indication relay 2RBK is therefore energized over channel 14, opening the circuits for relays LP and LPS and lighting lamp BKE.

After the operator has been advised that the switch has been unlocked, he restores lever 2WL to its normal center position. This again closes contacts a and b of lever 2WL momentarily to initiate the transmission of codes to both ends of the block. Relay 2WLP is released by the opening of contact c of lever 2WL, and it follows that in response to these codes relay 2WLS is operated to the left and relay 2RFS to the right, 4LFS remaining in its right-hand position. Relays 2LAR, 21HD and 2WAR release, relay 2RBP remains released and relay 2RBK energized, so that lamp BKE remains lighted.

When the train enters the main track, relay 2EAR releases, and when switch 2W is again locked in its normal position by the train crew, relay 2NWP becomes reenergized. As the train passes signal 24, relays 24HD, 4RAR and 4LBP release and the directional stick relay 22S becomes energized, and an indication code is initiated by relay 4LBP by which the block indication relay 4LBK is energized. When the train vacates the intermediate block section, relay 22HD becomes energized in the reverse direction, energizing relay 2RHD in the normal direction, energizing relay 2RBP which initiates a code by which relay 2RBK is released, but lamp BKE remains lighted due to the energization of relay 4LBK, until the train vacates the block. Signal 22 is conditioned to indicate caution, and the operator may move lever 2SG to the right and transmit a code to station No. 1 to reverse the signal control relay 2RHS if he desires, to permit signal 2RA or 2RB to be cleared for a following train.

Assuming next that with the right-to-left traffic direction set up as shown, that the switch 2W is to be unlocked to permit a train to enter the block and to move in the established direction, toward the left. In this case the operator moves lever 2WL to the left, energizing relay 2WLP and the lower winding of relay LP, holding relay LP in its left-hand position, and initiating codes by which relays 2WLS and 4LFS are operated to the right by relay 2WLP, and relay 2RFS is held in its left-hand position by relay LP, energizing the

line circuit system at both ends so that switch 2W may be unlocked, as in the preceding example.

Since in this instance the traffic direction is not changed, these operations may be carried out while the block is occupied by a preceding train, provided it has vacated the block section containing switch 2W. Thus if the left-hand section is occupied by a train moving toward the left, the directional stick relay 21S will be energized in lieu of relay 21HD, to supply current to relay 2WAR in response to the release of relay 2NWP, the operations in other respects being similar to those already described.

Although I have herein shown and described only one form of apparatus embodying my invention, it is understood that various changes and modifications may be made therein within the scope of the appended claims without departing from the spirit and scope of my invention.

Having thus described my invention, what I claim is:

1. Railway traffic controlling apparatus located at a central office for controlling traffic in a stretch of single track railway equipped with an entering signal at each end governed by a signal control relay and also governed in accordance with traffic conditions by a system of reversible circuits controlled jointly by traffic relays at the ends of the stretch, comprising a two position directional relay for designating traffic direction, a signal lever for each signal, a starting button for each lever effective when operated to actuate a starting relay associated therewith to initiate the transmission of a code reflecting the positions of the associated signal lever and of said directional relay, to which the signal control and traffic relays at the corresponding end of the stretch are responsive, signal indication relays controlled by the signals for indicating their condition and block indication relays controlled by said system of circuits for indicating when the stretch is unoccupied, a normally deenergized direction locking relay, a block indication repeating relay, a circuit for energizing said direction locking relay closed upon the operation of one signal lever or the other to its signal clearing position including contacts of the indication relays which when closed indicate that the signals are at stop and that the stretch is unoccupied, and also including a contact of the directional relay closed only when such relay occupies a position designating the traffic direction which is the opposite to that required in order to clear the signal controlled by the operated lever, circuits closed by the operation of the starting button for the operated lever when the direction locking relay is energized for operating said directional relay to the position required to establish the corresponding traffic direction, for energizing said block indication repeating relay and for actuating the starting relays associated with both signal levers to thereby initiate the transmission of codes to both ends of the block, a circuit for maintaining said directional locking relay energized after the directional relay is operated only until both starting relays are actuated, means controlled by said block indication repeating relay when energized for rendering said block indication relays ineffective to control said direction locking relay, and a circuit for maintaining said block indication repeating relay energized only until the block indication relays are again controlled by said system of circuits to indicate that the stretch is unoccupied.

2. Railway traffic controlling apparatus located at a central office for controlling traffic in a

stretch of single track railway equipped with an entering signal at each end governed by a signal control relay and also governed in accordance with traffic conditions by a system of reversible circuits controlled jointly by traffic relays at the ends of the stretch, comprising a two position directional relay for designating traffic direction, a signal lever for each signal, a starting button for each lever effective when operated to actuate a starting relay associated therewith to initiate the transmission of a code reflecting the positions of the associated signal lever and of said directional relay, to which the signal control and traffic relays at the corresponding end of the stretch are responsive, signal indication relays controlled by the signals for indicating their condition and block indication relays controlled by said system of circuits for indicating when the stretch is unoccupied, a normally deenergized direction locking relay, a circuit for energizing said direction locking relay closed upon the operation of one signal lever or the other to its signal clearing position including contacts of the indication relays which when closed indicate that the signals are at stop and that the stretch is unoccupied, and also including a contact of the directional relay closed only when such relay occupies a position designating the traffic direction which is the opposite to that required in order to clear the signal controlled by the operated lever, circuits closed by the operation of the starting button for the operated lever when the direction locking relay is energized for operating said directional relay to the position required to establish the corresponding direction and for actuating the starting relays associated with both signal levers, and a circuit for maintaining said direction locking relay energized after the directional relay is operated only until both starting relays are actuated.

3. Railway traffic controlling apparatus located at a central office for controlling traffic in a stretch of single track railway equipped with a reversible signal system, comprising a two position directional relay for designating traffic direction, a normally deenergized direction locking relay, circuits including front contacts of said direction locking relay and manually controllable contacts operable to different positions for operating said directional relay to corresponding positions to designate one traffic direction or another, block indication relays at the office controlled by traffic conditions to indicate when the stretch is unoccupied, a pick-up circuit for said direction locking relay including contacts of said block indication relays which when closed indicate that the block is unoccupied, and also including said manually controllable contacts and contacts of said directional relay closed only in non-corresponding positions, manually controllable relay means for setting up said signaling system in the direction indicated by said directional relay rendered effective by the energization of said direction locking relay, and a stick circuit for holding said direction locking relay energized following the reversal of said directional relay only until said manually controllable relay means is actuated.

4. Direction selecting apparatus for controlling traffic movements over a stretch of single track railway equipped with a reversible signaling system, a two position directional relay at a control office for designating traffic direction, a code communication system for transmitting manually initiated control codes reflecting the position

of said directional relay to stations at the ends of the stretch to control said signaling system, and for automatically transmitting indication codes from said stations reflecting the condition of occupancy of the stretch to control indication relays at the office, a normally deenergized direction locking relay, circuits including manually operable contact means for operating said directional relay from either of its two positions to the other position effective only when said direction locking relay is energized, and a circuit for energizing said direction locking relay including said manually operable contact means and contacts of said directional relay closed in non-corresponding positions and also including contacts of said indication relays which when closed indicate that the stretch is not occupied.

5. Direction selecting apparatus for controlling traffic movements over a stretch of single track railway equipped with a reversible signaling system, a two position directional relay at a control office for designating traffic direction, a code communication system for transmitting manually initiated control codes reflecting the position of said directional relay to stations at the ends of the stretch to control said signaling system, and for automatically transmitting indication codes from said stations reflecting the condition of occupancy of the stretch to control indication relays at the office, a normally deenergized direction locking relay, circuits including manually operable contact means for operating said directional relay from either of its two positions to the other position effective only when said direction locking relay is energized, a pick-up circuit for energizing said direction locking relay including said manually operable contact means and contacts of said directional relay closed in non-corresponding positions and also including contacts of said indication relays which when closed indicate that the stretch is not occupied, and a stick circuit arranged to hold said direction locking relay energized only until said code system is manually initiated to transmit codes reflecting the position of said directional relay to both said stations.

6. Direction selecting apparatus for controlling traffic movements over a stretch of single track railway equipped with a reversible signaling system, a two position directional relay at a control office for designating traffic direction, a code communication system for transmitting manually initiated control codes reflecting the position of said directional relay to stations at the ends of the stretch to control said signaling system, and for automatically transmitting indication codes from said stations reflecting the condition of occupancy of the stretch to control indication relays at the office, a normally deenergized direction locking relay, circuits including manually operable contact means for operating said directional relay from either of its two positions to the other position effective only when said direction locking relay is energized, a normally deenergized repeating relay, a circuit for energizing said direction locking relay including said manually operable contact means and contacts of said directional relay closed in non-corresponding positions and also including contacts of said indication relays which when closed indicate that the stretch is not occupied, and in parallel with said indication relay contacts, a front contact of said repeating relay, a pick-up circuit for said repeating relay closed in response to the manual initiation of a code when said direc-

tion locking relay is energized, circuit means effective when said locking relay and repeating relay are energized for locally operating said indication relays to the positions they assume in response to received codes indicating that the stretch is occupied, and a stick circuit for the repeating relay closed by the indication relays for maintaining the repeating relay energized until a code is received indicating that the stretch is unoccupied.

7. Direction selecting apparatus for controlling traffic movements over a stretch of single track railway equipped with a reversible signaling system, said stretch including a short detector section at each end, a two position directional relay at a control office for designating traffic direction, a code communication system for transmitting manually initiated control codes reflecting the position of said directional relay to stations at the ends of the stretch to control said signaling system and for automatically transmitting indication codes from each station to control a track indication relay to indicate the condition of occupancy of the corresponding detector section and to control a block indication relay in accordance with the condition of said signaling system to indicate the condition of occupancy of a portion of said stretch, the condition of the remainder of which is indicated by a similar block indication relay controlled by codes transmitted from the other station, a direction locking relay controlled by said indication relays, a repeating relay controlled by said direction locking relay, circuits including a manually operable contact means for operating said directional relay to either of its two positions effective only when said direction locking relay is energized, a circuit for energizing said direction locking relay including said manually operable contact means and contacts of said directional relay closed in non-corresponding positions and including contacts of said block indication relays which when closed indicate that the entire stretch is unoccupied, and in parallel with said indication relay contacts, a front contact of said repeating relay, said circuit also including contacts of said track indication relays each of which when closed indicates that the corresponding detector section is unoccupied, circuit means effective when said locking relay and repeating relay are energized for locally operating said block indication relays to the positions they assume in response to received codes indicating that the stretch is unoccupied, a stick circuit for the repeating relay closed by the indication relays for maintaining the repeating relay energized until a code is received which indicates either that the stretch is unoccupied or that a train has entered one of the detector sections, and means at each station for storing a code indicating the occupancy of the adjacent detector section until such code is transmitted.

8. Direction selecting apparatus for controlling traffic movements over a stretch of single track railway having an entering signal at each end, and a reversible system of circuits for controlling one signal or the other in accordance with traffic conditions in the stretch, a signal lever for each signal and a two position directional relay for controlling the direction of energization of said system of circuits, located at a control office, a code communication system for transmitting manually initiated control codes to stations at the ends of the stretch each of which reflects the position of said directional relay and of the lever

19

for the signal at the station to which the code is transmitted, and for automatically transmitting indication codes from said stations reflecting the condition of occupancy of the stretch, as indicated by said system of circuits when energized, to control indication relays at the office, a normally deenergized direction locking relay, a circuit controlled by each lever including a front contact of said direction locking relay closed when such lever is operated to reverse for clearing its signal, for operating said directional relay to the position for energizing said circuit system in the corresponding direction, and a circuit for energizing said direction locking relay including said reversed signal lever 15

20

contact and a contact of said directional relay closed only in the position corresponding to the opposite direction of traffic movements in said stretch, and also including contacts of said indication relays which when closed indicate that the stretch is unoccupied, and in parallel with said indication relay contacts, a normally open contact which is closed in response to the operation of said direction locking relay and is opened when said indication relays are again operated by codes received from the stations to indicate that the stretch is unoccupied.
